AUTOMATIC TELEPHONE SYSTEM

Edward S. Peterson, Elmwood Park, and Norman H. Saunders, Chicago, Ill., assignors, by mesne assignments, to Associated Electric Laboratories, Inc., Chicago, Ill., a corporation of Delaware

Application March 6, 1936, Serial No. 67,442

20 Claims. (Cl. 179—26)

The present invention relates in general to automatic telephone systems and more in particular to small automatic systems which are adapted for use in rural communities or other situations involving a limited number of subscribers. In a situation of this kind it is often desirable to have the subscribers' stations equipped with ordinary manual telephones, which may be of the local battery magneto type, and to provide for the control of the automatic switches from some remote point, generally a city exchange, where operators are available. The automatic system which forms the subject matter of this invention is of the foregoing character, and the object of the invention, therefore, may be stated as the provision of a new and improved remotely controlled community automatic exchange, commonly known as an R. C. X.

The invention will be described hereinafter with reference to the accompanying drawings, in which there is shown by means of the usual circuit diagrams sufficient of the equipment involved to enable the invention to be explained and understood.

Referring to the drawings, a subscriber's station is shown at A, Fig. 1, with a line 2—3 extending to the exchange, or R. C. X., where a line relay 4 is provided. A similar station B is indicated in Fig. 2. There may be a total of twenty-two subscribers' lines connected to the exchange.

Connections between the subscribers' lines are established by means of link circuits, each including a finder for connecting with calling lines and a connector for extending connections to called lines. One of these link circuits is shown in Figs. 1 and 2 of the drawings, and comprises the finder F, Fig. 1, and the connector C, Fig. 2, together with the relays and circuit connections shown. The finder F and connector C may be single motion rotary switches having twenty-five sets of contacts each. Of course larger switches could be used and the capacity of the system would be correspondingly increased. The number of link circuits provided depends on traffic requirements. Usually three or four links will suffice for an exchange of twenty-two lines.

The subscribers' lines are connected in multiple through the banks of all the finders and connectors. Thus in the case of the line of station A, the drawings show the connections of this line in the banks of finder F and it will be understood that the line is similarly connected in the banks of the other finders. The drawings also show the line of station A as having a set of so-called normal conductors which extend to the connector banks and are so labeled in the drawings. The line of station B is connected the same way, as are the other lines in the system.

The connectors such as C have to be directly operated in accordance with the numbers of

called lines, and to take care of this several control trunks may be provided, extending to another exchange where operators are available. One of these control trunks and the associated equipment is shown in Fig. 3.

The control trunk shown comprises the conductors 301 and 302. At the manual end the trunk terminates in jack J and associated equipment. At the R. C. X. the control trunk terminates in a link finder F', which has access to all the link circuits. The finder F' may also be a single motion rotary switch, and has sufficient sets of contacts to take care of the maximum number of link circuits that may be provided.

The R. C. X. is also provided with a storage battery, indicated by separate battery symbols in the drawings, for supplying operating current to the switches and relays. Some other source of direct current could, of course, be used. When a storage battery is supplied it is preferably connected to the trunk lines while they are not in use so as to charge from the battery at the main exchange. The connections are shown in Fig. 3, where it will be seen that the R. C. X. battery is connected to trunk conductor 302 at 231. At 25 the main exchange conductor 302 is normally connected to the exchange battery by way of K', 251, and 250. The R. C. X. battery is preferably a 12-volt battery and since the main exchange battery will have a voltage of at least 24-volts, 30 a regulating resistance 256 is used to adjust the charging current to the proper value.

It will be assumed now that the subscriber at station A, Fig. 1, desires to call the subscriber at station B, Fig. 2. To initiate the call the hand generator is operated. The ringing current energizes the line relay 4, which locks at 5. In operated position, relay 4 marks the associated line in the bank of finder F by ground at 6, and at 7 grounds the start lead 14.

The start relay 15 energizes over 14 (23, 52, 151, 112, 108), and closes the circuit of stepping magnet 28 at 18. The magnet 28 energizes and closes a circuit for stepping relay 16, whereupon relay 16 energizes and breaks the circuit of the stepping magnet. The magnet accordingly deenergizes, advances wipers 10—13 one step, and breaks the circuit of relay 16, which deenergizes and again closes the circuit of the stepping magnet. This interaction of 28 and 16 continues and the wipers 10—13 are advanced step by step in search of the calling line.

When the test wiper 12 reaches the marked test contact, a circuit is completed from ground by way of 6, 12, 19, 16, and 17 to battery, which holds relay 16 energized to prevent further operation of 28, and energizes relay 17. Relay 17 locks at 22, and opens the stepping magnet circuit at another point, as relay 16 will shortly be deenergized, due to closure of a circuit from ground at 60

44 by way of 21 and 11 to line relay 4, which shunts the lower winding of this relay and de-energizes it. The center winding of relay 4 is merely a resistance. The falling back of relay 4 of course breaks the test circuit over 12 and lets 5 16 fall back. Relay 17 also breaks the start circuit at 23, allowing start relay 15 to fall back and transfer the start circuit to the finder of the next link.

10 As additional results of the operation of relay 17, the two line conductors are closed at 20 and 27, the link is marked in the bank of finder F', at 26, and a start circuit for finder F' is closed at 25, the circuit extending from ground at 128 by 15 way of 125, 140, 25, 70, 233, and winding of start relay 202 to battery.

On energizing, relay 202 closes a circuit for stepping magnet 204 of finder F'. On energizing, stepping magnet 204 closes a circuit for stepping 20 relay 203, and the latter breaks the magnet circuit at 219. Magnet 204 and relay 203 accordingly interact and the former advances the wipers 210—214 in search of the link in use by the calling line.

25 When the link is found a circuit is completed from ground by way of 209, 203, 218, 211, 71, 26, and 53 to battery, which holds up stepping relay 203 and energizes relay 209. The holding of relay 203 stops the finder. On energizing, relay 209 30 closes the trunk at 231 and 232, and locks itself at 230, the locking circuit extending from ground by way of 209, 230, 214, 75, 42, 54, 141, and relay 105 to battery. On energizing, relay 105 opens the link finder start circuit at 128. Relay 105 also 35 closes a circuit for the buzzer relay 106 at 127. Relay 106 short circuits itself and operates as a buzzer. The lower winding of relay 106 is bridged across the talking conductors of the link and accordingly a tone is transmitted over the calling 40 line which notifies the calling party that his call is receiving attention.

Returning to relay 209, this relay transfers the link finder start circuit at 227, allowing start relay 202 to fall back. Relay 203 also deenergizes, 45 following relay 202, as the latter opens the test circuit at 218. Relay 209 also closes a circuit for relay 206 at 228. Relay 206 operates relay 205. The latter locks itself and opens the circuit of relay 206, which falls back after an instant, being 50 slow acting. During the interval in which relay 206 is operated, the battery is connected to the trunk conductor 301 at 220, completing a circuit from the battery over 220, 222, 232, 301, winding of R', K, K', 252, and drop D to ground. The 55 drop is thus released to signal the operator.

Answering the call, the operator restores the drop by hand and plugs into the jack J. The cord circuit may be of any suitable and well known type. When the plug is inserted in jack J 60 relays 255, 254, and 257 pull up successively. Relay 255 disconnects the exchange battery from trunk conductor 302 at 251, connects the trunk conductors together at the same point, and at 253 extends both conductors to battery by way of the 65 calling device key K2. Relay 257 also opens the normal battery connection at 250, and cuts off the drop at 252. This arrangement insures that the exchange battery, normally on the line to charge the battery at the R. C. X., will be cut off before 70 the dialling battery at the calling device is connected, so that a higher voltage battery can be used for dialling if desired. Usually, however, the regular main exchange battery will be of high enough voltage. The two slow acting relays 256 75 and 257 also delay reconnecting the exchange

battery to the trunk when the plug is withdrawn. The reason for this will be explained later.

When relay 255 connects battery to both sides of the trunk, a circuit is completed that can be traced from battery by way of key K2, 253, K', K, 5 301, 232, 222, 220, 213, 74, 143, lower left-hand winding of R, contacts controlled by 150, and winding of line relay 103 to ground. On the closure of this circuit relay 103 energizes and closes a circuit for slow relay 190, which energizes and 10 closes a circuit for slow relay 104. Relay 104 prepares the operating circuit for connector C at 124, and at 123 closes a circuit for relay 102, which energizes. At 117 relay 102 breaks the circuit of buzzer relay 106 and closes a circuit for relay 33, 15 at 118 relay 102 disconnects the lower winding of relay 106 from across the line and substitutes the A. C. relay 100. Also at 150 relay 102 closes through the other side of the trunk to the line relay 103 and removes the normal short circuit 20 from the lower winding of differential relay 101. The line relay 103 is now held energized over a simplex circuit including the two trunk conductors 301 and 302 in parallel. Relay 101 is differentially wound and does not energize. The circuit over 25 trunk conductor 302 parallels the one previously traced over 301 and will be obvious. It may be stated that this circuit is normally open at 150 in order to prevent premature operation of line relay 103 when the trunk is first connected through 30 by operation of relay 209.

Relay 33 energizes when its circuit is closed by relay 102. The opening of contacts 59 and 54 does not deenergize relays 17 and 105 because these contacts are now shunted at 122 and 125 35 of relay 104. Relay 33 also opens a point in the circuit of start relay 15 at 52, and effects certain other circuit changes which need not be noticed now.

It will be observed now that the calling party 40 at station A is in communication with the operator, assuming the latter has thrown the listening key in her cord circuit. The line 2—3 has been extended via wipers 10 and 13 of finder F and contacts 20 and 27 of relay 17 to the home 45 position contacts which are associated with wipers 110 and 113 of connector C. These wipers are connected with the right-hand windings of repeating coil R and the left-hand windings of the repeating coils are bridged across the trunk 50 301—302 through wipers 212 and 213 of finder F'. The operator now answers in the usual manner to ascertain the wants of the calling party.

The calling party may or may not have removed his receiver. It may be stated in this 55 connection that although a call is ordinarily extended through to a trunk promptly in the manner described, there exists the possibility of a delay due to the operator being busy or to all 60 links being in use, and the subscribers may be instructed that after putting in a call the receiver need not be removed until the operator calls back. When the operator answers, therefore, if she hears no one on the line she will 65 operate the ringing key in her cord circuit to signal the calling party.

The transmission of ringing current back over trunk line 301—302 operates the A. C. relay 100, Fig. 2. Relay 100 closes a circuit for relay 32 which pulls up and makes itself slow acting by 70 short-circuiting its upper winding. This is to guard against possible chattering of relay 100. Relay 32 shorts the condenser at the repeating coil R at 45, which improves the ring-through characteristics of the repeating coil and enables 75

the bell at the calling station A to respond. The efficiency of the ringing circuit over the line to station A is also improved by the operation of the line relay 4 which pulls up and locks at the beginning of the ringing operation, removing its upper winding from in bridge of the line. The operation of the line relay 4 at this time does not start the finder in the next link because relay 32 closes a circuit for the common relay 80 at 49, and relay 80 disconnects the starting ground from contacts of all line relays such as 4. The line relay 4 is enabled to lock up during ringing because relay 32 removes ground from wiper 11 at 44. When the operator finishes ringing, one short ring is usually sufficient, relays 100 and 32 fall back, also relay 80. The latter is slow-acting so that line relay 4 is shunted down by the closure of 44 before starting ground is again connected up at the contacts of 80.

When the party at station A hears his bell ring he will remove his receiver and tell the operator what number he wants. If the wanted number is that of a subscriber in the main exchange the operator will complete the call in known manner using the other end of the cord now plugged up in jack J. There is nothing in these operations that requires explanation, except the fact should be noted that when the conversation is over the subscriber at station A can give a disconnect signal by ringing off according to standard practice. The relays 100 and 32 respond to ringing current from the line the same as they did when the operator rang, and relays 80 and 4 also operate. Thus the subscriber at station A is able to ring through and operate the supervisory relay in the operator's cord. The operation of this relay may also be used to recall the operator, as is well known.

When the operator pulls down the connection, relay 255 falls back, followed at short intervals by slow relays 254 and 257. Relay 255 disconnects the dialling battery from the trunk line, breaking the circuit of line relay 103, which falls back and breaks the circuit of slow relay 100. Relays 100, 104, 102, and 33 now fall back successively. In the interval between the falling back of relays 104 and 33 the locking circuit of relay 17 is opened at 50 and 122 and relay 17 falls back. The finder wipers stay where they are, awaiting the next call. In the same interval between the falling back of relays 104 and 33 the locking circuit of relay 209 is opened at 54 and 126, and relay 209 deenergizes, also relay 105. Relay 209 gets back before relay 257 at the main exchange, so the trunk is opened at 231 before the main exchange battery is connected up at 258, which is necessary to prevent reenergization of line relay 103. In the interval between the falling back of line relay 103 and relay 104 an impulse is sent via 40, 121, and 124 to stepping magnet 108 of connector C and the wipers 110—113 are advanced one step. This prepares the restoring circuit, however, which is completed when relay 33 falls back, the circuit extending from ground at 51 by way of 144, interrupter contacts of magnet 108, strapped bank contacts, wiper 112, and winding of 108 to battery. Magnet 108 operates automatically over the above circuit and drives the connector wipers to home position. Relay 107 energizes in parallel with magnet 108 and holds up while the wipers are moving over the banks in order to prevent interference with the subscribers' lines. The link and

trunk line are now in normal condition or idle condition.

It will be assumed now that the subscriber at station A puts in a call as before described and gives the operator the number of a local station in the R. C. X., the number of station B, for instance, which is 993. The connector C is a so called adding type connector and it responds to one, two, or three digits to select a desired line. The contact sets reached by dialling the digit 9 at 10 and the two digits 99 (see bank of wiper 110) are resting positions and have no lines connected.

When the operator receives the number of the local R. C. X. station she knows she has to dial back over the trunk line to complete the connection and therefore she operates the dial key K2 associated with the trunk in use. This inserts the calling device CD in the circuit of line relay 103, which is in energized condition along with relays 100, 104, 102, and 33 which it controls. The operator next dials the three digits of the called number.

Responding to the first digit 9, the line relay 103 deenergizes nine times and sends nine impulses to the stepping magnet 108 which advances the wipers 110—113 to the ninth set of contacts, or to the first resting position. The operator is disconnected from the calling line as soon as wipers 110 and 113 leave home position. Relay 100 of course holds on during dialling. Relay 107 operates to open circuit wipers 110 and 111 at 129 and 130 and prevent interference with lines momentarily contacted during movement of the wipers. On the second digit 9 the line relay and magnet 108 advance the wipers to the second resting position, and on the third digit 3 the wipers are advanced to the set of contacts associated with the line of station B, as can be seen clearly from the drawings.

There is no automatic busy test; but the operator, having completed dialling and restored her key K2, listens on the line and then challenges if necessary to ascertain if the line is busy or not. It will be assumed first that the line is busy.

Having ascertained that the called line is in use, the operator actuates key K for several seconds, or long enough to give the connector C plenty of time to restore. The operation of key K opens one side of the trunk and the line relay 103 holds over the other trunk conductor alone. Also one winding of differential relay 101 gets no current and the relay operates on the other winding, closing a circuit for relay 34. The latter relay closes the homing circuit of the connector C from ground at 51 by way of 55, 57, 144, interrupter contacts of magnet 108, wiper 112, and winding of magnet 108 to battery. When the switch comes to rest in home position the trunk is again connected to the calling line through wipers 110 and 113, and the operator can inform the calling party at station A that the called line is busy. If the operator withdraws her plug from jack J now the link and trunk are restored to normal, as previously explained.

Returning now to the point where the called line 993 was connected with, it will be assumed that the line is found to be idle. The operator then actuates her ringing key, transmitting ringing current over the trunk line and through the connector wipers 110 and 113 to the called line. Contacts 39 and 43 of relay 31 are shunted by small condensers which permit enough ringing current to leak back to the calling line to give the calling party the usual ringing signal. The ringing operation is similar to the ringing opera-

tion already described in connection with station A. Relays 100 and 32 respond, and the latter relay short circuits the condenser in repeating coil R and also removes ground from wipers 111 of the connector. The latter operation enables line relay 4' to respond at the first application of ringing current and clear itself off the line. Relay 80 is also energized to prevent relay 4' from starting a finder when it energizes. When relay 32 falls back at the end of the ringing operation, relay 80 restores, and the line relay 4' is shunted down again. The operation of relay 32 produces a further result in this case due to connector C being off normal. Each time relay 32 energizes it operates relay 35, but the operation of the latter relay is of no consequence unless the connector C has been operated, in which case relay 35 locks up over a circuit which extends from ground at 119, 145, lower winding of 35, 56, 144, interrupter contacts of magnet 108, wiper 112, and winding of magnet 108 to battery. In operated position relay 35 prepares a circuit for relay 31 at 57.

Having finished ringing, the operator brings about the final connection of the calling and called lines by momentarily operating key K. This key opens one side of the trunk line and permits relay 101 to energize as previously explained. Relay 101 operates relay 34, which closes a circuit for relay 31 at 55, since relay 35 is now energized. Relay 31 energizes, locks itself at 38, and connects the calling and called lines at 39 and 43. At 40 relay 31 opens the impulsing circuit, and at the same point closes a circuit for relay 104. At 42 relay 31 opens a point in the locking circuit of relay 109, but the circuit is not opened because contacts 42 are now shunted by contacts 191 of relay 190.

The operator may now withdraw her plug from jack J, which disconnects the dialling battery from the trunk and breaks the circuit of line relay 103. Relay 103 and slow relay 190 accordingly fall back, but relay 104 stays operated due to the circuit now closed at 40 by relay 31. When relay 190 falls back it opens the shunt around contacts 42 at 191, and thus breaks the locking circuit of relay 109, which falls back and restores the trunk to normal condition.

When the subscriber at station B answers his telephone the conversation can go ahead. The talking circuit is a full metallic circuit without inductive connections in the link. When the subscribers are through talking they hang up their receivers and ring off as is standard practice. The ringing current operates relay 100, which operates relay 32, as previously explained. Relay 32, since relay 31 is now energized, closes a circuit for relay 30 from ground at 48 by way of 38 and 47. Relay 30 energizes and opens 36, but relay 31 stays locked to ground at 48. When the ringing ceases relays 100 and 32 fall back, with the usual results. Also relay 32 breaks the circuits of relays 31 and 30 at 48. Relay 30 is slow acting so relay 31 gets back first and opens its locking circuit at 38 before it can be closed at 36. When relay 31 deenergizes it breaks the circuit of relay 104 at 40. The deenergization of relay 104 is followed by the deenergization of relays 102, 35, 33, and 17, and the link is restored to normal. Relay 33, it will be noted, closes the homing circuit of connector C at 51.

If the subscribers fail to ring off the link is released by the timer T. When relay 31 energizes it closes a circuit for the timer at 37. The timer is a thermostat, adjusted to close its contacts

after a predetermined interval such as five minutes. When the timer operates its contact it closes a circuit for relay 30, which unlocks relay 31 and the link is restored as previously explained.

It will be assumed now that the operator receives a call from a subscriber in the main exchange who desires to be connected with a station such as B in the R. C. X. To complete this connection the operator plugs into a trunk jack such as J, which operates the associated finder such as F' to connect with an idle link in the R. C. X., and the operator then dials the connector of the link on to the desired line.

When the plug is inserted in jack J, relays 255, 254, and 257 operate as already explained, with the result that the normal charging circuit is opened, the drop is cut off, and the dialling battery is connected to both conductors of the trunk line. Battery being connected to trunk conductor 301, an obvious circuit is completed for relay 207, which energizes, locks itself on to the trunk at 224, and opens both sides of the trunk at 222 and 223. A circuit is also closed for relay 208, the function of which is to prevent the subsequent energization of relay 209 from operating relays 205 and 206. Finally, relay 207 closes a circuit for start relay 202 at 226, and prepares the test circuit at 225.

Consideration should now be given to the fact that all the links at the R. C. X. may be busy, in which case the finder F' would not be able to find an idle link. Each link has two terminals such as 82 and 83, Fig. 1, which are included in a chain circuit. At the first link terminal 82 is connected to ground and terminal 83 is connected to terminal 82 of the next link. Terminal 83 of the second link is connected to terminal 82 of the third, and so on, except that terminal 83 of the last link is connected to a common relay 200. Now if all the links are in use the chain circuit will be completed, for in each link contacts such as 24 or 120, or both, will be closed, and relay 200 will be energized. Relay 200 opens the circuit of start relay 202 at 215, or rather prevents this circuit from being closed at 226 by the operation of relay 207. Relay 200 also sets the buzzer relay 201 in operation, and connects the upper winding of such relay to the trunk, whereby a tone current is transmitted over the trunk to the operator to inform her that no links are available. The operator can then wait on the trunk until the tone disappears, as it will do when a link becomes idle, or she can withdraw her plug and tell the calling party to call again.

Assuming now that the link shown in Figs. 1 and 2 is available for use, the common relay 200 will not be energized when the operator plugs into the trunk, and when start relay 202 operates it will close the circuit of the stepping magnet 204 at 217. The stepping magnet 204 and stepping relay 203 now interact as previously described and the former begins to step along the wipers 210—214. The idle condition of the link is denoted by the presence of battery potential on conductor 72 by way of 26 and 53. When the finder wipers reach the link shown, therefore, assuming this is the first one found idle, wiper 210 will pick up the battery potential, closing a circuit for holding stepping relay 203 and energizing relay 209. Holding up relay 203 stops the finder F' by holding 219 open. Relay 209, on energizing, locks itself in series with relay 105 in the link, as previously explained. Relay 105 makes the link busy to local subscribers by open-

ing the circuit of start relay 15 at 151. Relay 209 shifts its contacts 231 and 232, but the trunk is not extended through because relay 207 is still energized. It will be noted that the latter relay is not cut off from the trunk at 232 because it is locked at 224. Relay 209 also closes a locking circuit for relay 208, to prevent this relay from falling back when relay 207 deenergizes. Also the circuit of start relay 202 is broken at 229 and the transfer of the starting circuit takes place at 227.

The R. C. X. battery is normally bridged across the trunk line through relay 207, but is cut off at 231 when relay 209 pulls up. This produces a click in the operator's receiver which is recognized by her as a signal that an idle link has been found. To seize the link the operator now momentarily operates key K. This disconnects battery from conductor 301 and permits relay 207 to drop back. Relay 207 cuts itself off from the trunk at 224 so that it cannot energize again when the key is restored, and closes the trunk through at 222 and 223. The line relay 103 does not energize over conductor 302 because this side of the simplex control circuit is open at 150. When key K is restored the dialling battery is reapplied to conductor 301 and the line relay 103 energizes. Following the operation of the line relay, relays 190, 104, 102, and 33 pull up, with results previously explained. It may be mentioned, however, that the opening of contact 53 of relay 33 makes the link busy to another finder such as F' that might be started up by the operator.

The equipment is now ready for dialling to begin, and the operator may operate her dial key K2 and then operate the calling device CD in accordance with the number of station B or any other station. The operation of the connector C responsive to dialling has already been described and it will not be necessary to go over this again, nor to explain how the link and trunk are restored, as this has also been explained before.

The key K' which is associated with the trunk line along with keys K and K2 is not strictly necessary, but may be supplied as a convenient means for clearing both sides of the trunk of battery and ground connections.

The system herein described is primarily intended for individual line service, but nevertheless it is capable of handling party lines with a limited number of stations on each line. The line of station B is therefore indicated as having a second station B'. The stations on a party line can signal each other by code ringing with their hand generators and so far as this phase of the system operation is concerned there could be the usual number of stations on each line. The limit is imposed by the fact that on calls from the main exchange to the R. C. X. the operator has to ring through the repeating coils R' and R, and with repeating coils now in general use the ringing current at a connected line being signalled from the main exchange is inadequate to satisfactorily operate more than three or four ringers. The number of stations on a line therefore should not ordinarily be greater than four. When a party line subscriber rings another subscriber on his own line he of course rings up his line relay such as 4' at the same time, which brings the call in to the operator at the main exchange. It is usually preferable, therefore, to instruct party line subscribers to call the operator for every connection even though a party on the same line is desired.

At the same time, in an emergency, such as would exist if the links were all busy, the hand generator method of code ringing is available and can be used.

The invention having been described, that which is believed to be new and for which the protection of Letters Patent is desired will be pointed out in the appended claims.

What is claimed is:

1. In a telephone system, a first exchange, 10 links in the first exchange, each comprising a finder and a connector, trunks leading from the first exchange to a second exchange, each trunk terminating at the first exchange in a finder which has access to said links, means for setting up a connection from the first exchange to the second by operating successively the finder of an idle link and the finder of an idle trunk, and means for setting up a connection from the second exchange to the first by operating the finder 15 of an idle trunk to connect with an idle link and by then directly controlling the connector of the selected link.

2. In a telephone system, a first exchange, 20 links in the first exchange, each comprising a finder and a connector, trunks extending from the first exchange to a second exchange, means for establishing connections from the first exchange to the second by way of the finder of any link and any trunk, means for setting up connections from the second exchange to the first 25 by way of any trunk and the connector of any link, the link connectors being excluded from the former connections and the link finders from the latter, means for setting up connections local 30 to the first exchange by way of the finder and connector of any link, and means for controlling the establishment of local connections over any trunk.

3. In a telephone system, a plurality of links 35 for connecting calling and called lines, a plurality of trunk lines associated with said links and extending to an operator's position, means responsive to a call for connecting an idle link and an idle trunk, means for extending the call to the called line responsive to directive impulses transmitted over the trunk, said means including a line relay in the link responsive to said impulses, means for imposing a control condition on the trunk to which the line relay is non-responsive, and means responsive to said control condition for completing the call through the link and for disconnecting the same from the trunk.

4. In a link circuit, a finder, a connector, and 45 circuits over which the finder wipers are connected to the connector wipers through bank contacts normally engaged by the connector wipers.

5. In a link circuit, a finder, a connector, 50 means including the home position bank contacts of the connector for connecting the finder wipers with the connector wipers before the connector is operated, and relay contacts for connecting the finder wipers with the connector 55 wipers after the connector is operated.

6. In a telephone system, a link comprising a 60 finder and a connector, a trunk, and circuits for connecting the finder wipers with the trunk by way of the connector wipers and contacts normally engaged thereby.

7. In a telephone system, a link comprising a 65 finder and a connector, means for operating said finder to connect with a calling line, a trunk, means responsive to the completion of the con- 70

75

- nection to the calling line for connecting said trunk to the wipers of said connector, and circuits leading from the wipers of the finder to normally occupied contacts in the bank of the connector, whereby the connected calling line is extended to said trunk.
8. In a telephone system, a link comprising a finder and a connector, a trunk, means for connecting said trunk with a calling line through wipers of the connector and finder in serial relation, and means for connecting the trunk with a called line through wipers of the connector alone.
9. In a telephone system, a link comprising a finder and a connector, means for operating said finder to connect with a calling line, a trunk, means for connecting the trunk with the link, means for operating and restoring said connector over the trunk at will while maintaining the trunk connected to the link, and circuit connections over which the trunk is connected to a called line when the connector is operated and to the said calling line when the connector is restored.
10. In a telephone system, a link comprising a finder and a connector, a trunk, means including the finder in operated position and the connector in normal position for connecting a calling line with said trunk, means for operating the connector over the trunk to connect with a called line, thereby breaking the connection between the trunk and the calling line, and means controlled over said trunk for restoring said connector to reestablish the connection between the trunk and the calling line.
11. In a telephone system, a switch, a control circuit for said switch including the two sides of a line in parallel, means for operating said switch responsive to momentary interruptions of both sides of said line, means for interrupting one side of said line while maintaining the other side closed, and means responsive to such interrupting of only one side of the line for restoring said switch to normal.
12. In a telephone system, a link comprising a finder for connecting with a calling line and a connector, a trunk associated with said link, means for controlling said connector over said trunk to connect with a called line, a relay in the link responsive to ringing current received over the trunk, means for imposing a characteristic control condition on said trunk, and means responsive to said control condition for establishing a talking connection through said finder and connector or for restoring the connector, depending on whether said relay has been operated or not.
13. In combination, a line, a line relay at one end of the line normally connected to only one conductor thereof, whereby the line relay will not respond when a current source is connected to the other conductor, means for connecting a current source to both conductors of the line at the end remote from the line relay, thereby energizing the line relay over the conductor to which it is connected, a slow acting relay controlled by said line relay and held in operated position during momentary deenergizations of said line relay, and means including said slow relay for connecting said line relay to the conductor from which it is normally disconnected, whereby the line relay may be controlled from the said current source at the remote end of the line over both conductors of the line in parallel.
14. A dialling circuit including the two sides of a line in parallel, means for connecting a current source to both sides of said line at one end, a line relay at the other end initially energized over only one side of the line, and means controlled by said line relay while the same is energized or only momentarily deenergized for including the other side of the line in its energizing circuit.
15. In combination, a trunk line, a line relay connected to the first conductor at one end, means at the other end for connecting a current source to both conductors, thereby energizing said line relay, a double wound differential relay, a slow-acting relay controlled by said line relay, means including said slow relay for connecting said line relay to the second conductor of said line and for connecting the two windings of said differential relay in the two conductors of said line, respectively, in series with said line relay, and means for interrupting the connection of said current source to one of said conductors, whereby the line relay is maintained and the differential relay is operated over the other conductor.
16. In a telephone system, a ringing circuit including a trunk line and a subscriber's line, a repeating coil included in the connection between the trunk line and the subscriber's line, control circuits superimposed on said trunk line and requiring a condenser to be included in series with the repeating coil windings which are connected to the trunk line, a relay associated with the repeating coil and responsive to ringing current when the ringing circuit is used, and means including said relay for short circuiting said condenser to give the repeating coil the necessary ring through characteristics.
17. In a telephone system, a subscriber's line, a relay bridged across said line and responsive to ringing current coming from the station on said line or from the exchange, switching apparatus controlled by said relay, and means for preventing said relay from controlling said apparatus if it is operated by ringing current from the exchange.
18. In a telephone system, a subscriber's line, a line relay for said line responsive to ringing current when the line is calling to start a finder, said relay also responsive to ringing current when the line is called, and means for preventing said relay from starting a finder when the line is called.
19. In a telephone system, a plurality of links, each including a finder for connecting with calling lines, means in each link for connecting with called lines, means for ringing connected called lines, means common to said links for preventing the operation of the said finders, and means in each link effective while a called line is being rung from such link for rendering said common means effective.
20. In a telephone system, an automatic exchange, a group of links for completing local calls in the exchange and for completing calls incoming from another exchange, a group of trunks incoming from said other exchange, each trunk terminating in a finder having access to said links, means controlled from a link when the same is in use for a local call for starting the finder terminating an idle trunk and causing such finder to find the link, and means controlled over a trunk on an inter-exchange call for starting the finder associated therewith and for causing the same to find and connect with an idle link.
